CHESSBOROUGH JAMES HENRY MACKENZIE-KENNEDY, OF NEW YORK, N. Y.

TOILET ARTICLE

Application filed December 22, 1931. Serial No. 582,604.

The present invention relates to a brush of novel construction and more particularly to a brush especially adapted for association with and combined with a comb for simultaneous use therewith.

While combination articles comprising a brush and comb have been heretofore suggested, the proposed articles have had an inherent disadvantage in that use of the comb 10 in normal position has prevented effective action of the brush. Not only have the proposed articles been inefficient, but they have possessed a further impracticability due to their bulkiness. It is a principal object of 15 the present invention to provide a brush of such construction as to cooperate with the utmost effectiveness with a comb in simultaneous use therewith, the combined article, furthermore, being of inconsiderable thickness 20 so that it may be conveniently carried in a restricted space, as in a pocket, hand bag, or the like.

Since the principles of construction underlying the invention will be most readily understood from a description of the actual embodiment, I shall proceed with reference to the accompanying drawing, wherein:

Figure 1 is a side elevation of a brush constructed in accordance with the present invention and shown in combination with a comb,

Figure 2 is a section on line 2-2 of Figure 1,

Figure 3 is a sectional view similar to that of Figure 2, but on a larger scale and partly diagrammatic, and

Figure 4 is a sectional view of a modified form of combination article differing principally from the article of Figures 1 to 3 40 in the tuft arrangement of the brush.

Referring to the drawing, and first to Figures 1 to 3, reference numeral 5 designates a relatively thin brush stock in and along the bottom of which, and at one side thereof, are set the alternate series of bristle tufts 6 and 7. The outer ends or mouths of the holes 8 and 9, which, as here shown, receive the tufts to anchor the same, are preferably substantially in alignment, the axial lines of the holes, however, diverging toward the top

of the stock. At its other side, the stock bottom is provided with a dovetail groove in which is slid the mating back portion 10 of a comb 11 whose teeth are indicated at 12. If desired, the portion 10 may be permanently engaged in the groove or it may have such a sliding frictional engagement therewith as to enable the parts to be used in combination or to be disassembled for separate use.

The disposition of the comb teeth relative to the tufts 6 and 7 is such that the outer ends of the latter occupy an area closely confined to the side of the teeth so as not to impede manipulation of the comb at the natural angle to the scalp or similar surface. The comb moving in advance of the tufts, the hair tends to climb between the tuft bristles without causing any substantial backward bending of the latter, particularly of the bristles 7. As has been mentioned, the axial lines of holes 8 and 9 are angularly related. The angles are preferably such that the axial lines of tufts 6 diverge from the longitudinal axial lines of the comb teeth at about a 20° angle, while the axial lines of tufts 7 converge toward the teeth ends at about a 5° angle. The tufts, as a whole, of the two series, are in criss-cross relation to each other.

It will thus be evident that with the comb being moved, in use, at its ordinary angle of inclination to the scalp with the brush following the comb, the bristles of tufts 7 will assume an even sharper angle of inclination to the scalp than the comb teeth and will be moved substantially end-wise into and through the hair, so that the bristle ends are caused to penetrate to the roots of the hair and the separate hairs are caused to move inwardly of the tufts between the bristles with an ever-increasing tensioning and frictional effect as they approach the base of the tufts. The bristles have what may be termed a plowing action affording vigorous treatment not only to the hair, but to the scalp as well. The diverging tufts 6 have a minor plowing effect as compared to the tufts 7, but on the other hand they have an added smoothing effect in the nature of the effect secured by the ordinary brush. Thus, to the action of

the comb a greatly intensified action is added by the bristles 7, bristles 6 cooperating and adding a smoothing function so that the individual hairs are given a treatment longitudinally and substantially circumferentially complete.

The criss-cross tufts emerge from the stock, as mentioned, in substantially aligned openings, so that the use of an exceptionally thin stock is made possible. The combined article may thus be of minimum thickness which is an important consideration from the standpoint of convenience and entirely consistent with its principle of operation which requires a relatively narrow bristle area closely adjacent the comb teeth.

According to Figure 4, the comb teeth as at 13, are made integral with the stock 14. Alternated series of tufts 15 and 16 are set in holes 17 and 18 in the overhanging portion of the stock, the holes being staggered, as shown. The axial lines of the holes 17 and 18 are divergent toward the top of the stock, so that the free ends of the tufts are substantially in alignment and disposed closely adjacent the teeth 13. Tufts 15 are convergent with respect to the comb teeth, preferably at an angle of about 5°, and have the functions ascribed to tufts 7, above. Tufts 16 are somewhat divergent from the comb teeth and function as tufts 6, above described.

It is obvious that many variations in details may be made without departure from the scope of the invention. The form of comb shown is merely illustrative and the material of which the comb is made may be selected to suit preference or requirement. The bristle series need not necessarily be longitudinally coextensive with the comb and the length of the tufts relative to the comb teeth may be chosen with regard to the conditions to be met. Tufts may be arranged at both sides of the comb and the shape of the individual tufts is subject to wide variation. All useful applications of the brush or combined article are contemplated under the present invention as defined in the following claims.

I claim:

1. As a new article of manufacture, the combination of a comb, a thin brush stock extending along the comb above the teeth thereof and in connection therewith, and bristles set in said stock and projecting alongside the teeth of the comb, the outer ends of the bristles occupying an area closely confined to the sides of the teeth so as not to impede manipulation of the comb at the natural angle to the scalp or similar surface, whereby, the article being manipulated with the comb in advance of the bristles, the hair tends to climb the bristles without substantial backward bending of the free ends of the latter.

2. An article according to claim 1 wherein the bristles are arranged in two series of anchored tufts, the tufts of one series being

alternated with and in angular relation to the tufts of the other series.

3. An article according to claim 1 wherein the bristles are arranged in two series of anchored tufts, the tufts of one series being alternated with and in angular relation to the tufts of the other series, the anchored ends of all the tufts being substantially in alignment at the locality of emergence from the stock.

4. An article according to claim 1 wherein the bristles are arranged in two series of anchored tufts, the tufts of one series being alternated with and in angular relation to the tufts of the other series, the outer ends of all the tufts being substantially in alignment.

5. As a new article of manufacture, the combination of a comb, a thin brush stock extending along the comb above the teeth thereof and in connection therewith, said stock being provided with holes whose longitudinal axes are directed toward the points of the teeth and tufts of bristles secured in said holes with their outer ends adjacent the teeth of the comb and extending toward the points of the teeth, the outer ends of the tufts occupying an area closely confined to the sides of the teeth so as not to impede manipulation of the comb at the natural angle to the scalp or similar surface.

6. As a new article of manufacture, the combination of a comb, a thin brush stock extending along the comb above the teeth thereof and in connection therewith, said stock being provided with holes whose longitudinal axes are directed toward the points of the teeth and tufts of bristles secured in said holes with their outer ends adjacent the teeth of the comb and extending toward the points of the teeth, at an angle of about 5° to the longitudinal axis of the teeth, the outer ends of the tufts occupying an area closely confined to the sides of the teeth so as not to impede manipulation of the comb at the natural angle to the scalp or similar surface.

7. As a new article of manufacture, the combination of a comb, a thin brush stock extending along the comb above the teeth thereof and in connection therewith, said stock being provided with holes whose longitudinal axes are directed toward the points of the teeth, said holes alternating with other holes whose axes diverge from the first named axes, and tufts of bristles secured in said holes, the outer ends of the tufts in the holes first specified being directly adjacent the teeth and directed toward the points of the latter, and the outer ends of the tufts in the second specified holes being divergent from the outer ends of first named tufts.

8. As a new article of manufacture, the combination of a comb, a thin brush stock extending along the comb above the teeth thereof and in connection therewith, said stock being provided with holes whose longitudinal axes are directed toward the points

of the teeth, said holes alternating with other holes whose axes diverge from the first named axes, and tufts of bristles secured in said holes, the outer ends of the tufts in the holes
5 first specified being directly adjacent the teeth and directed toward the points of the latter at an angle of about 5° to the longitudinal axes of the teeth, and the outer ends of the tufts in the second specified holes be-
10 ing divergent from the longitudinal axes of the teeth at an angle of about 20° .

In testimony whereof I affix my signature.
CHESSBOROUGH JAMES HENRY MACKENZIE-KENNEDY.
